UNITED STATES PATENT OFFICE

2,434,526

BODY ATTACHED UMBRELLA

Ulysses Thornton, Chicago, Ill.

Application April 22, 1946, Serial No. 664,097

1 Claim. (CL 224—5.1)

1

The primary aim of the present invention is to provide a protective device of the afore-described character which will be particularly useful to persons required to be exposed to inclement weather and who are required to use their hands and arms thereby making it impossible for such persons to carry a conventional umbrella.

Still a further object of the invention is to provide a body supported umbrella of extremely simple construction capable of being quickly and easily applied to or removed from the person of the wearer.

Other objects and advantages of the invention will hereinafter become more fully apparent from the following description of the drawing which illustrates a preferred embodiment thereof, and wherein:

Figure 1 is a front elevational view showing the body attached umbrella in an applied position;

Figure 2 is a side elevational view thereof;

Figure 3 is a horizontal sectional view taken substantially along the line 3—3 of Figure 1;

Figure 4 is a perspective view of a part of the umbrella frame;

Figure 5 is an enlarged sectional view taken substantially along the plane of the line 5—5 of Figure 2; and

Figure 6 is an enlarged sectional view taken substantially along a plane as indicated by the line 6—6 of Figure 3.

Referring more particularly to the drawings, the numeral 7 designates the body attached umbrella in its entirety; said umbrella including a convexo-concave frame designated generally 8. The frame 8 includes a plurality of longitudinally bowed radially disposed supporting ribs 9 connected where they intersect at the apex of the frame 8 by fastening means 10. Said frame 8 is formed of any suitable metal and includes a ring 11 forming the base thereof, to which the ends of the ribs are connected by being bent therearound and soldered as seen at 12 in Figure 6. The frame 8 provides a support for a piece of water-proof fabric 13 which is stretched thereover and the edge of which is turned back upon itself around the base ring 11 and attached in any desired manner.

The frame 8 is supported by pairs of corresponding uprights 14 as best illustrated in Figure 4. Each of the pair of uprights 14 is formed from a single strand of heavy gauge wire or the like, the terminals of which are fastened to strips 15, which, in turn, are secured between pairs of strips 16 by fastenings 17. The ring 11 is secured between the upper ends of strips 16 by other fas- 55

tenings 17. The intermediate portion of each of the supports 14 is bent to provide a transversely disposed, upwardly bowed shoulder engaging member 18. The shoulder engaging members 18 each terminate at their ends in U-shaped portions or loops 19. One leg of each portion 19 is formed by the lower end of an upright 14.

The frame 8 and its covering 13 is supported in position above the head of the user, as illustrated in Figures 1 and 2 through engagement of the portions 18 with the shoulders of the wearer. To maintain the umbrella in applied position, a body engaging belt 20 of any suitable material, such as leather or fabric, encircles the chest of the wearer, beneath the armpits and is detachably secured across the chest by means of a buckle or other suitable clasp 21. As best illustrated in Figure 2, the belt 20 extends through the U-shaped portions 19 and is fastened thereto in any suitable manner as by stitching at 22. The legs of the shoulder engaging portions 18 and the lower portions of the uprights 14 are disposed at the front and back of the shoulders of the wearer, as seen in Figures 1 and 2. The uprights 14 may be flared outwardly intermediate of their ends to any extent, depending upon the diameter of the frame 8.

The edge of the covering may be clamped to the ring 11 by the upper ends of the strips 16, if desired.

From the foregoing it will be readily apparent that the umbrella 7 may be demounted from the person of the wearer by unfastening the buckle or clasp 21 and sliding the shoulder engaging portion 18 off of the arms of the wearer. In view of the foregoing, a further description of the operation and use of the umbrella is considered unnecessary.

Various modifications and changes are contemplated and may obviously be resorted to without departing from the spirit and scope of the invention as hereinafter defined by the appended claim.

I claim:

45 In a body attached umbrella, supporting means comprising two strands of relatively heavy gauge wire, each of said strands having an upwardly bowed intermediate portion forming a shoulder engaging member and upwardly extending end portions forming supporting legs diverging upwardly from the ends of the shoulder engaging member thereof, said strands being provided with loops, at the junctions of the shoulder engaging members and legs, a body encircling belt connected to said loops for maintaining the shoulder

engaging portions in applied position, and a covering member attached to the upper ends of the supporting legs and supported thereby in a position above the head of the wearer.

ULYSSES THORNTON.
